UNITED STATES PATENT OFFICE.

ADAM SCHWEBEL, OF NEW HAVEN, CONNECTICUT.

IMPROVED NUT-MACHINE.

Specification forming part of Letters Patent No. **69,256**, dated September 24, 1867.

To all whom it may concern:

Be it known that I, ADAM SCHWEBEL, of the city and county of New Haven, in the State of Connecticut, have invented certain new and useful Machinery for Making Forged Nuts; and the following is a full, clear, and exact description of the same, reference being had to the accompanying drawings, making a part of this specification, in which—

Figure 1 represents a plan or top view of the machine, showing the double-acting working parts right and left. Fig. 2 represents a longitudinal side elevation of the machine, the left-hand portion of one side being broken off, showing a sectional view of the working mechanism. Fig. 3 is a detached view of a cross-section, showing a face view of the crowning dies to form the faces of the nuts. Fig. 4 shows a detached view of a broken-off section through the mechanism for holding and turning the nuts for hammering the edges.

The object of my invention is to make forged iron nuts of all the ordinary sizes required in the various arts and manufactures, and finish them uniformly in the most perfect manner, and with the greatest facility.

My invention consists in the construction, arrangement, and combination of the mechanism hereinafter described, both in matters of detail, mechanical movements, and operation, referring to the drawings, and to the letters of reference marked thereon.

The same letters or characters indicate the like parts of the machine in all of the figures.

In constructing my engine or improved machine for making forged nuts I use the best quality of iron and steel.

The side pieces or longitudinal portion of the frame, A A, are made from one pattern of cast-iron, and are supported at the ends on four legs, B B, under frames or cross-pieces C C, which may be of any desired length, in proportion to the required width of the machine, for making twelve, eighteen, twenty-four, or more nuts at one and the same time.

In the center of the engine, on the top of the side pieces, A A, is secured a straight bar of iron or steel, a a, to form a rest or support for the bar of iron from which the nuts are cut and forged. On each side of this center bar, a, are movable frames D D, in which are

fitted and secured by screws a series of cutting-dies, c c c c, they being so arranged in relation to each other, and their movement right and left, so that they alternately form dies and punches, cutting the bar clear, without waste.

Each of the dies c c c c, having a round hole in the center of its face, forms the matrix, into which the punches d d d d enter as they punch the round holes in the center of the nuts, which is done at the same time that the nuts are cut from the bar, there being an opening on the under side of each of the dies c c c c to let the scrap fall out.

The nuts, as they are cut and punched through the center, are retained on the round punches d d d d, then in the spaces between the die-punches c c c c, which are narrowed back of the cutting-faces, so that the nuts are free to be lifted out of their places by the action of the semi-rotating bars E E, to which the punches d d d d are attached, so that the nuts are carried over on the punches and placed in position on the crowning-die bars F F, to be taken off onto the spindles f f f f, where they are held and turned for compressing, hammering, and finishing.

The frame D, to which the cutting-dies c c c c and the semi-rotating bar E are secured to operate, have long guide-bars G G resting on the top of both sides of the frame or longitudinal side pieces, A A, and are worked by the cams g g, between the double bearings of the journals j j, on the main operating-shafts H H, at both ends of the machine, as seen in Fig. 1, where one of the caps J J J is removed, the power for cutting and punching the nuts being applied to the bars G G by the cams g g; and the withdrawing movement is effected by the rock-shafts I I and cams h h on the shafts H H, on the outside of the frame. On the top of the sides A A are fitted two other sliding frames, K K, with guide-bars k k, the same being operated by the cams l l, made with cams g g on the shafts H H. These motions are for the purpose of compressing the nuts into the concave recesses i i i of the the crowning-dies F F, to round the corners and finish the faces of the nuts, and also to discharge them from the spindles f f when completed.

Between the longitudinal side pieces, A A, are fitted other sliding frames, M M, on which is mounted the series of spindles f f f f, they being provided with pinions m m m m and racks L L, the same being operated by levers N N and cams n n on the shafts H H, so that the nuts will be turned one-fourth over, right and left, as the four sides are being compressed or hammered for finishing, the sliding frames M M being operated by cams O O on the end shafts, H H, and held back by springs o o, attached to the cross-pieces C C.

The crowning-die bars F F are made to slide up after the nuts have been removed from the punches d d d d onto the spindles f f f f, so that the concave recesses i i i are centrally with the nuts. These movements are effected by the rock-shaft P and levers p p', and cam Q on the opposite end of the shaft H, and the spiral springs q q in the center underneath.

For compressing or hammering the edges of the nuts square, after they are placed on the spindles f f f f, I use long heavy flat bars or plates R R', the width of the inside of the frame, one of them being above and the other below the series of the nuts as they are in a position to be turned and finished; the hammers R R' being held in position and operated by the vertical sliding bars r r r r, so connected with rock-shafts S S that when put in motion by the lever s by the cogs t t on the periphery of the wheel T, the force of the blows is applied to the bottom and top edges of the nuts at the same instant, they being alternately turned automatically right and left between each blow until finished, when the spindles f f f f are withdrawn, and the nuts are discharged underneath.

The automatic movements given to the punches d d d d for reversing the face side of the nuts after they are cut out by the die-punches c c c c, and placing them in the position to be forged and finished in the manner above described, are somewhat intricate and not easily defined.

The broken-off section of one side of the machine, as seen in Fig. 2, shows one-half of the mechanism, which consists of loose cams U U on the central bottom shaft, u, to which chains or wire cords V V are attached and pass under small pulleys v v, one on the outside, the other on the inside, of the pulley, and extend up to and take a half-turn around the semi-rotating shaft or bars E E, so as to turn them the reverse way, either right or left, at the same time, the motion being effected by the cams W, on the center of the shaft u, acting on the rock-shafts X in the center of the machine above, the arm w being connected by a coupling-bar, x, to the loose cam U. There being duplicates of this portion of the mechanism to reverse the position of the punches d d d d on both sides of the frame, produces the automatic movements both ways in their proper course.

To hold the bar of iron from which the nuts are cut firmly upon the rest a a, I arrange a follower, Y, suspended to the arms y y of a rock-shaft, Y', so that it is not in the way of placing the heated bar in the machine between the face of the cutting-dies.

The first movement of the machine is to bring the edge of the follower Y onto the bar by the action of the lever Z, on the outside of the frame, and rod z, which connects the lever Z with the rock-shaft Y', by a pin, d, on the inside of one of the series of spur gear-wheels 1, 2 2, 3 3, which connects the mechanism and produces the harmonious automatic movements, right and left, of the entire machine.

The sliding frames, which have their support on the longitudinal side pieces, A A, and the cams which operate them and other portions of the working mechanism into which extraneous matter might be liable to get to wear or obstruct the working of the machine, I cover with the caps J J and A' A'.

It will readily be seen that in my improved engine or machine for making forged nuts, as above described, any number of cutting-dies and punches may be used, according to the size of the nuts, the thickness of the metal used for them, and the width and capacity of the machine, which does not require any more cam or other movements to forge fifty nuts than it would to make five, in the same perfect manner.

Having thus fully described my invention and its mode of operation, what I claim as new, and desire to secure by Letters Patent, is—

1. The combination of the two series of cutting-dies c c with the moving frames D D, when arranged and made to operate as described.

2. I claim the combination of the two series of cutting-dies, the series of punches, and the semi-rotating shafts, arranged as described, with any suitable means for rotating said shafts, in the manner and for the purposes set forth.

3. I claim the combination of the sliding frame D, semi-rotating shaft E, and series of punches, arranged and operating substantially as described.

4. I claim the combination of the series of punches d d with the series of spindles f f, and means, substantially as herein described, for transferring the nuts from the punches to the spindles.

5. I claim the combination of the crowning-die plate F, made as described, with recesses in its upper edges for the reception of the punches, with the sliding frame K and spindles f f, substantially as set forth.

6. I claim the combination of the rock-shaft Y and frame y y with the rest a and means for causing said frame y y to descend and hold the bar from which the nuts are to be cut, substantially as described.

7. I claim the combination of the oscillating and vertically-sliding plates R R', operated substantially as described, with the series of spindles f f, as and for the purposes set forth.

semi-rotating shafts E E, for operating the same alternately right and left, in the manner herein described, for the purposes specified.

ADAM SCHWEBEL.

8. I claim the combination of the cam rock-shaft, converting-bar u, loose cams w w, pulleys v v, and chains V V or cords with the
